UNITED STATES PATENT OFFICE.

CHARLES TURNER, OF MANCHESTER, ENGLAND.

APPARATUS FOR APPLYING AND MAINTAINING PRESSURE PERIODICALLY.

Application filed November 6, 1926, Serial No. 146,830, and in Great Britain November 18, 1925.

This invention relates to an improved apparatus for applying and maintaining pressure periodically, for use, for example, in opening and closing firmly a valve in a shale 5 distillation system, wherein it is desired to operate a valve periodically, or in shearing machines, die-stamping, embossing and similar machines wherein periodic pressure is desired.

According to the invention the apparatus 10 comprises a rock shaft, a lever arm rigidly connected to the rock shaft and adapted to be connected to the valve or other part to be actuated, a member loosely mounted on the rock shaft and connected through a yieldable 15 connection to the arm rigid on the rock shaft and a rotary cam adjacent to the rock shaft and adapted to engage the loosely mounted member to rotate the rock shaft through said arm and yieldable connection and thus actuate the valve or other part; and means for 20 producing and maintaining an augmented pressure on such part during a certain period of the rotation of the cam.

In a suitable construction the shaft having 25 the rigid lever for connection to the part to be actuated carries an arm which is yieldingly connected by one end to a plate or the like loose on the shaft. The end of the plate remote from the point of connection to the 30 arm carries a pivoted tripod plate on which are mounted two rollers, the movement of the tripod being limited by suitable stops.

The cam is arranged on a rotary shaft 35 parallel to the first-named shaft and is so shaped that, on rotation of said rotary shaft, said cam engages the free end of the plate, which is suitably shaped, turning the plate on the rock shaft connected to the part to be actuated. The cam turns the plate into an 40 approximately horizontal position to move the part to be actuated, and the cam in its further movement successively engages the rollers to produce an augmented pressure to hold said part in the position into which it 45 has been moved, the yielding connection of the plate to its shaft enabling this to be done. Continued movement of the cam causes the pressure to be removed and the cam leaves the rollers and the plate without jolting or 50 shock, the actuated part then being moved by gravity into its initial position and turning the shaft to which it is connected into the original position for engagement by the cam at the proper period.

55 By regulating the rotation of the cam the part to be actuated can be moved into the de-

sired position and pressure applied thereto automatically and at any desired intervals.

To enable the invention to be fully understood, it will now be described by reference 60 to the accompanying drawings in which:

Fig. 1 is a side elevation of one embodiment of the invention shown for illustrative purposes as applied to a valve such as is used 65 in a shale distillation process.

Figs. 2, 3, 4 and 5 are views illustrating the several stages of operation of the apparatus and Fig. 6 is an end view at a right angle to Fig. 1.

As in Fig. 1, the part to be actuated (shown 70 as valve 6) is carried by a lever rigidly connected to a shaft 7, and is adapted to be moved into the desired position when the shaft 7 is rotated through 90° in a counter-clockwise direction. Loosely mounted on 75 the shaft 7 is a pair of plates 8, and an arm 9 has one end rigidly secured to the shaft between the plates. The other end of the arm is yieldingly connected to the plates 8 by an eye-bolt 10 passing through a block 11, piv- 80 otted between the plates 8, a coiled spring 12 being arranged within the block between a shoulder on the eye bolt and a bush 13 screwed into the block 11. The spring 12, therefore, is free to slide on the bolt 10 as 85 shown and tends to hold the ends of the plates 8 with which it is associated away from the outer end of the arm 9. Between the free ends of the plates 8 a tripod 14 comprising 90 a pair of plates is pivoted on a pin 15 fixed in the plates 8. Between the two plates of the tripod 14 a pair of rollers 16, 17 are pivotally mounted, movement of the tripod being limited by the stops 18, 19 extending between the plates 8. The ends of the plates 8, adjacent to the tripod 14 are inclined to the side edges of said plates for engagement with a pair of rollers 20 mounted on an arm 21 having a cam face shaped as shown and fixed 95 to a shaft 22 parallel to the rock shaft 7. Obviously a single plate may be substituted for the pair of plates 8.

The operation of the above described apparatus is as follows:

With the parts in the position shown in 105 Fig. 1, the valve 6 or other part to be actuated is in one position and, if the shaft 22 is rotated in a clockwise direction, the rollers 20 of the arm 21 engage the shaped ends of the plates 8 moving the plates into the position shown in Fig. 2, consequently rotating the shaft 7 through the arm 9 and moving 110

the valve 6 or other part to be actuated into the desired position. Continued movement of the arm 21 is designed to apply pressure to hold the actuated part in said position. 5 As shown in Fig. 2, the tripod 14 has been moved by gravity into contact with the stop 18 and the cam face of the arm 21 engages the roller 16. Further movement of the arm 21 causes the portion A of the cam face, 10 which is an arc struck from the centre of shaft 22, to slide over the roller 16 until the toe of the cam face rests on the roller 17 (Fig. 3). The toe of the cam face is formed with an inclined portion B and, as the arm 15 21 continues to move, pressure is exerted on roller 17 by the portion B. As the roller 17 is depressed the tripod is rocked on its pivot, the roller 16 is raised, and the tripod 14 moves away from the stop 18 into the position shown 20 in Fig. 4. In this position the pressure transmitted by the cam face of the arm 21 is transmitted through the yielding connection between the plates 8 and arm 9 and rocks the shaft 7 and consequently the valve 6 or other 25 part to be actuated is pressed firmly into the position into which it has been moved. Continued movement of the arm 21 causes its cam face to reach the position shown in Fig. 30 5 in which the tripod 14 rests against the stop 19 and the torsion on the shaft 7 is released so that, as the cam face of the arm 21 leaves the roller 17, no jolt occurs and the valve 6 or other actuated part is free to move into its initial position by the sole action of gravity 35 or by the weight of material resting upon it.

It will be understood that, since the weight of the arm 9, sleeve 11 and associated parts are greater than that of the tripod 14, when the cam face of the arm 21 leaves the plates 8, 40 the parts return automatically to the position shown in Fig. 1.

The arm 21 may be adjustably mounted on the shaft 22 and rotated at any desired speed, either continuously or intermittently according 45 to the desired operation of the actuated part.

For example, where the apparatus is to be used for actuating the valve of a retort, the valve operating gear will be arranged 50 outside the retort and the shaft 7 may, if desired be suitably operated outside the retort independently of the cam mechanism, by hand or otherwise when it is desired to open or close the valve.

55 Obviously the invention may be applied for operating a series of valves in a retort system.

In the example illustrated, the valve to be operated upon is shown as directly and rigidly connected to the shaft 7, but obviously 60 the apparatus may be arranged to operate upon a valve or the like not directly or positively connected to the shaft.

I claim:

1. Apparatus for applying and maintaining pressure periodically for the purposes 65

described, comprising a rock-shaft, a lever rigidly connected to said shaft and adapted to be connected to a part to be operated, a member loosely mounted on said shaft, a second member mounted to rock on said loosely mounted member and having portions projectable during its rocking movement beyond an edge of said loosely mounted member, an arm rigid on said shaft, a yieldable connection between said loosely mounted member and said arm, and a rotary cam having means adapted during a part of its rotation to engage one end of the loosely mounted member to rock the shaft and move the part to be operated into desired position; said cam having portions adapted during further rotation of the cam to successively engage the projectable portions of said rocking member and exert an augmented pressure on the part to be operated through said loosely mounted member and yieldable connection. 70 75 80 85 90 95 100

2. Apparatus according to claim 1 wherein stops are carried by the loosely mounted member to engage and limit the rocking movement of the rocking member in both directions during engagement of the cam with portions of said rocking member. 105

3. Apparatus for applying and maintaining pressure periodically for the purposes described, comprising a rock-shaft, a lever rigidly connected to said shaft and adapted to be connected to a part to be operated, a member loosely mounted on said shaft, an arm rigid on said shaft, a hollow block carried by the loosely mounted member, means longitudinally adjustable in said hollow member, and a spring in said hollow member having its opposite ends bearing against said longitudinally adjustable member and the arm, and a rotary cam adapted to engage the loosely mounted member to rock said shaft and move the part to be operated into desired position and thereafter exert an augmented pressure on the part to be operated through said hollow block, adjustable means and spring. 110 115 120 125 130

4. Apparatus for applying and maintaining pressure periodically, comprising a rock-shaft, a pair of spaced members loosely mounted between their ends on said shaft, a member pivoted between said plates, said member having parts arranged in triangular relation to its pivot and adapted, respectively, when said member is rocked in opposite directions on its pivot, to project beyond the edges of said spaced members, a lever secured to said shaft and adapted, when said shaft is rocked in one direction, to exert pressure on a part to be actuated, an arm secured to said shaft, yieldable means between said arm and said spaced members, and a rotatable cam adapted in its rotation to first engage and rock said spaced members and exert pressure through said yieldable means, said arm, said rock-shaft and said lever upon the part to be actuated and then to successively engage the 130

projecting parts of said pivoted member and exert further pressure through said yieldable means, said lever, said rock-shaft and said arm upon the part to be actuated.

5 5. Apparatus according to claim 4 wherein the member pivoted between the spaced members is triangular in shape and the parts adapted to project beyond the edges of the spaced members comprise antifriction mem-
bers.

10 6. Apparatus for applying and maintaining pressure periodically to a part to be actuated, comprising a rock-shaft, a pair of spaced plates loosely mounted between their ends on said shaft, each of said plates having one of its ends inclined with relation to its side edges, a member pivoted between said spaced plates on an axis parallel to said rock shaft and having parts arranged in triangu-
lar relation to its pivot adapted, respectively,

15 20 to project beyond the edges of said spaced

plates when said member is rocked in opposite directions, a pressure applying member secured to said shaft and adapted, when said shaft is rocked in one direction, to apply pressure to a part to be operated, an arm having one end secured to said shaft, a yieldable connection between the other ends of said plates and said arm, an arm rotatable on an axis parallel to said rock-shaft, and anti-friction members and a cam face carried by said rotatable arm, said antifriction members adapted during part of the rotation of said rotatable arm to engage the inclined ends of said spaced plates and said cam face adapted during further rotation of said arm to successively engage the projecting parts of said pivoted member.

25 30 35 In testimony whereof I have signed my name to this specification.

CHARLES TURNER.
